UNITED STATES PATENT OFFICE.

MATTHEW GEORGE BECKER, OF CHICAGO, ILLINOIS.

DESIGN FOR A BOX-TRAY OR ARTICLE OF SIMILAR NATURE.

58,538.

Specification for Design.

Patented Aug. 2, 1921.

Application filed December 9, 1919. Serial No. 343,608. Term of patent 3½ years.

To all whom it may concern:

Be it known that MATTHEW GEORGE BECKER, a citizen of the United States of America, residing at Chicago, in the county of Cook and State of Illinois, has invented a new, original, and ornamental Design for a Box-Tray or Article of Similar Nature, as shown in the accompanying drawing and described in the following specification.

The figure is a top plan view of the tray showing my new design.

I claim:

The ornamental design for a box tray or article of similar nature as shown.

MATTHEW GEORGE BECKER.

Witnesses:

EARL RAYMOND HAMILTON,
CORINNE M. ROSELLE.
